UNITED STATES PATENT OFFICE.

WILLIAM R. LEE, OF GALENA, KANSAS.

RATCHET MECHANISM.

Application filed July 20, 1925. Serial No. 44,883.

To all whom it may concern:

Be it known that I, WILLIAM R. LEE, a citizen of the United States, and a resident of Galena, in the county of Cherokee and 5 State of Kansas, have invented a new and useful Improvement in Ratchet Mechanisms, of which the following is a full, clear, and exact description.

My invention relates to improvements in 10 ratchet mechanisms, and it consists in the combinations, constructions and arrangements herein described and claimed.

An object of my invention is to provide a 15 ratchet mechanism of the character described in which the locking pin may be made to disengage the ratchet teeth and permit movement of the member carrying the ratchet teeth with respect to the member carrying the pin in a direction opposed to the normal 20 direction of travel of the ratchet toothed member when the pin is engaging with the teeth thereof.

A further object of my invention is to 25 provide a ratchet mechanism of the character described in which the locking pin is operatively disengaged with the ratchet teeth by mere movement of the tooth-bearing member with respect to the locking pin bearing member.

30 A further object of my invention is to provide a ratchet mechanism of the character described which is particularly well adapted for use in reversible ratchet wrenches and the like.

35 A further object of my invention is to provide a ratchet mechanism of the character described which is extremely simple in construction, which is automatic in operation, and which is thoroughly efficient for 40 the purpose intended.

Other objects and advantages will appear in the following specification, and the novel features of the invention will be particularly pointed out in the appended claims.

45 My invention is illustrated in the accompanying drawings, forming part of this application, in which

Figure 1 is a plan view of a wrench embodying my improved ratchet mechanism,

50 Figure 2 is a section view along the line 2-2 of Figure 1,

Figure 3 is a view of the outer peripheral wall of a part of the device illustrated in Figure 1, laid in a common plane,

55 Figure 4 is a modified form of my inven-

tion showing the bottom view of a lock nut embodying my improved ratchet mechanism,

Figure 5 is a view of an engaging surface for the lock nut illustrated in Figure 4,

Figure 6 is a modified form of my invention incorporated in an extension ladder embodying my improved ratchet mechanism,

Figure 7 is a section view along the line 7-7 of Figure 6,

Figure 8 is a view along the line 8-8 of Figure 6, and

Figure 9 is still another modified form of my invention.

In carrying out my invention, I make use of a pair of movable elements, one having 70 ratchet teeth and the other a locking pin. In Figures 1, 2 and 3 I have shown this structure embodied in a wrench in which 1 is a work-engaging member, such as found in the ordinary type of socket wrench. This 75 member is substantially annular in contour and is rotatably mounted within an annular body member 2. The body member 2 has a handle portion 3 by means of which the body member may be rotated so as to impart rotative movement to the member 1 through my improved ratchet mechanism.

This mechanism consists in a spring 80 pressed longitudinal member locking pin 4 which is also free to swing laterally in a 85 plane in common with the axes of the members 1 and 2, (see Figure 2). The spring 5 for actuating the locking pin 4 is adjustable as to tension by provision of a threaded plug 6 which is projected within a threaded bore 90 7 extending longitudinally of the handle member 3 within which the pin is also partially disposed.

The outer peripheral wall of the member 1 is shown in Figure 3 and the peculiar 95 structure of this wall comprises the principal features of my invention. This wall is substantially divided into two courses A and B by the provision of broken partition walls 8. The course A has a plurality of ratchet 100 teeth 9 for engaging with the pin 4 to prevent rotation of the member 1, in the present case in a clock-wise direction as viewed in Figure 1. The course B has a plurality 105 of ratchet teeth 10 which are constructed so as to prevent rotation of the member 1 in a counter clockwise direction, as viewed in Figure 1, by engagement of the pin 4 therewith.

It is thus apparent that if the locking 110

pin 4 is in registration with the course A, that the member 1 may not rotate in a clockwise direction, but is free to rotate in a counter-clockwise direction, and that if the 5 locking pin 4 is in registration with the course B, that the converse is true.

Each of the adjacent inclined surfaces of the teeth 9 and 10 adjacent to their lowermost ends are connected by means of an 10 oblique groove 11 so as to cause the locking pin 4 to be guided laterally from one lane to the other where reversal of movement of the member 2 carrying the pin is performed after the pin has moved more than 15 one-half of the distance between the preceding tooth and the succeeding tooth.

From the foregoing description of the various parts of the device, the operation thereof may be readily understood. Let us 20 assume that it is desired to tighten a nut upon a bolt. The head of the nut is projected through the bore 12 in the member 1 and the handle 2 moved in a clockwise direction. Assuming that the locking pin 4 25 is in registration with the course B, the pin will engage with a tooth 10 and cause the member 1 to be rotated in a clockwise direction. When the handle 3 has been turned as far as the work will permit, the handle is 30 moved in a counter-clockwise direction so that the pin 4 passes over the teeth 10 and over the edge 13 of the groove 11. The mechanic will become accustomed to the clicking of the pin as it passes over the teeth 10 35 and the edges 13, and will know that every second click will bring the pin again into registration with the teeth 10 so that for clockwise movement of the member 1, two, four, six or eight clicks as the handle is 40 moved in a counter-clockwise direction, will maintain the pin in registration with the teeth 10 in the course B.

Let us assume now that it is desired to 45 unfasten the nut. To this end, the handle 3 is moved so that but one click is heard provided of course that the pin is in registration with the teeth 10 and not in the groove 11 or the end of the groove. This will guide the pin through the groove 11 into the course 50 A, whereupon rotation of the handle 3 in a counter-clockwise direction will move the member 1 therewith. The same rule as to counting the clicks of the pin over the teeth 9 and the adjacent edge 14 of the groove 11 55 will apply to operation of the member 1 in a counter-clockwise direction.

What I have thus provided is a ratchet mechanism which is automatically reversible by the mere movement of one of the two elements with which the teeth and the locking pin, respectively, are associated.

In Figures 4 and 5 I have shown a modified form of my invention in which my improved ratchet mechanism is embodied in a 60 nut lock consisting of a nut 20 having a pair 65

of endless courses A and B corresponding to the courses A and B shown in Figure 3 formed on the bottom wall of the nut and disposed concentric with the axis of the nut. The course B has teeth 21 corresponding 70 with the teeth 10 shown in Figure 3. These teeth are disposed so as to engage with a laterally movable locking pin 22 mounted for lateral movement upon a washer 23 which is fixed against movement in any well 75 known manner with respect to the bolt upon which the nut is used so as to normally prevent rotation of the nut in a counter-clockwise direction. This structure prevents the nut from turning back off the bolt under 80 normal conditions when the pin 22 which corresponds to the pin 4 is in engagement with the teeth 21.

Guide grooves 24 corresponding to the grooves 11 shown in Figure 3 are employed 85 for conducting the pin 22 from the course B to the course A in precisely the same manner as the pin is conducted from the course A to the course B in Figure 3. Thus when it is desired to remove the nut from the bolt, 90 the nut is turned so that the pin drops into the groove 24 at 25 and is then turned in a counter-clockwise direction so as to guide the pin into the course A, whereupon continued rotation will remove the nut from 95 the bolt.

It should be understood at this time that while I have shown one locking pin 22 that two locking pins may be used, one ahead of the other so as to cause one of the two pins 100 to engage with one of the teeth 21 with relatively less movement of the nut than required with one pin.

In Figures 6, 7 and 8, I have shown still a further modified form of my invention 105 which is particularly well adapted for use with extension ladders. Referring to Figure 6, I have shown two sections C and D of an extension ladder, which sections are secured against lateral movement apart from 110 one another by the provision of guide members 26 and 27.

The upper end of the section C has a pivotally mounted spring pressed dog 28 disposed therein which is yieldingly projected 115 toward the section D. The sections C and D are arranged for longitudinal movement with respect to one another so that the section D may be moved above the section C as in extending the ladder. My improved ratchet mechanism when applied to the extension ladder is for the purpose of preventing the section D from falling downwardly 120 with respect to the section C, and to this end two sections A and B identical to the courses A and B shown in Figure 4, but in vertical alignment, are formed on the innermost face 29 of the section D. The course B has teeth 30 corresponding to the teeth 21 shown in Figure 4 which engage with 125 130

the pin 28 when the pin is in registration with the course B to prevent the section D from moving toward the section C.

Guide grooves 24^a corresponding to the 5 guide grooves 24 shown in Figure 4 are provided for conducting the locking pin 28 from the course B to the course A when the section D is raised so as to permit the 10 pin to fall below the portion 25^a of the grooves 24^a. Thus the section D may be lowered or locked in position while elevated at will.

It should be noted at this time that if the ladder is intended for use with the section D 15 suspended and the section C depending below the section D as in the case of the fire ladder, and which must also be available for use with the section C resting upon the 20 ground and the section D disposed upon the section C, that the ratchet teeth may be identical in arrangement with those courses A and B illustrated in Figure 3.

In Figure 9 I have shown still a further modified form of my invention which is 25 primarily intended for installation upon the outer side walls of a window sash. The locking pin employed with this form of the invention is identical with the locking pin 28 shown in Figures 6 and 7. The courses 30 A and B are constructed with the teeth of the ratchet 32 in the course B arranged so as to stop downward movement of the sash.

The course A consists of a single conducting groove extending longitudinally of the 35 sash and parallel with the aligned teeth 32. The guide groove 24^b is formed at the lowermost end of the sash beneath the lower of the teeth 32 which is provided for the purpose of moving the pin 28 into registration with the course A when the sash is 40 moved clear to the top, thus upon lowering the sash the pin may pass along the course B and permit the unobstructed downward movement of the sash.

When the sash has reached the bottom of 45 its travel, the pin will fall over the portion 33 and into a groove 34 which will conduct the pin back into the course B when the sash is raised again.

It should be noted that such an arrangement of teeth as shown in Figure 8 may be 50 employed in place of the arrangement shown in Figure 9 in the window sash if desired, which construction will permit of the lowering 55 of the sash at intermediate points in its upward travel.

I claim:

1. As a machine element, a ratchet mechanism comprising a member having a spring 55 pressed locking pin, a second member associated with the first named member, said members being movable with respect to one another, said second named member having a wall formed with a pair of parallel courses, 60 each course having ratchet teeth formed

therein for engaging with the locking pin, the teeth in one course having their pin-engaging portions facing in a direction opposite to the pin-engaging portions of the remaining course, said member being further provided with grooves for guiding the pin from one course to the other. 70

2. As a machine element, a ratchet mechanism comprising a member having a spring 75 pressed locking pin, a second member associated with the first named member, said members being movable with respect to one another, said second named member having a wall formed with a pair of parallel courses, each course having ratchet teeth formed there- 80 in for engaging with the locking pin, the teeth in one course having their pin-engaging portions facing in a direction opposite to the pin-engaging portions of the remaining course, said member having a groove for 85 guiding the pin from one course to the other.

3. As a machine element, a ratchet mechanism comprising a member having a spring 90 pressed locking pin, a second member associated with the first named member, said members being movable with respect to one another, said second named member having a wall formed with a pair of parallel courses, each course having ratchet teeth formed 95 therein for engaging with the locking pin, the teeth in one course having their pin-engaging portions facing in a direction opposite to the pin-engaging portions of the remaining course, said member having grooves connecting the two courses with one 100 another for guiding the locking pin from one course to the other, said grooves communicating with the courses at each end at points adjacent to the lower parts of the inclined surfaces of the ratchet teeth. 105

4. A ratchet mechanism as a machine element, a member having a spring pressed locking pin, a second member associated with the first named member, said members being movable with respect to one another, said second named member having a wall 110 formed with a pair of parallel courses, one of said courses having a plurality of ratchet teeth formed therein for engaging with the locking pin, said member being further provided with a groove for guiding the pin from one course to the other. 115

5. A ratchet mechanism as a machine element, a member having a spring pressed locking pin, a second member associated with the first named member, said members being movable with respect to one another, said second named member having a wall 120 formed with a pair of parallel courses, one of said courses having a plurality of ratchet teeth formed therein for engaging with the locking pin, said member being further provided with spaced apart grooves for guiding the pin from one course to the other. 123

WILLIAM R. LEE.
